(74) Attorney, Agent, or Firm — Shartsis Friese LLP;
Cecily Anne O'Regan(57) **CLAIM**

The ornamental design for a predrill guide tool, as shown and described.

DESCRIPTION

FIG. 1 is a front perspective view of predrill guide tool;
FIG. 2 is a front view of predrill guide tool;
FIG. 3 is a back view of predrill guide tool;
FIG. 4 is a left side view of predrill guide tool;
FIG. 5 is a right side view of predrill guide tool;
FIG. 6 is a top view of predrill guide tool;
FIG. 7 is a bottom view of predrill guide tool; and,
FIG. 8 is a rear perspective view of predrill guide tool.
